UNITED STATES PATENT OFFICE.

CHARLES E. HUNTOON, OF CHICAGO, ILLINOIS.

CENTER-BEARING.

1,162,925.

Specification of Letters Patent.

Patented Dec. 7, 1915.

Application filed April 17, 1914. Serial No. 832,457.

To all whom it may concern:

Be it known that I, CHARLES F. HUNTOON, a citizen of the United States, residing at Chicago, in the county of Cook and State 5 of Illinois, have invented certain new and useful Improvements in Center-Bearings; and I do hereby declare the following to be a full, clear, and exact description of the invention, such as will enable others skilled 10 in the art to which it appertains to make and use the same.

My invention relates to the construction of center bearings for railway vehicles and especially to that class of center bearings, 15 now well known, in which anti-friction devices are interposed between the truck center plate and the body center plate thereof.

More specifically still, my invention is designed to be particularly applicable to those 20 anti-friction center bearings in which the balls or other anti-friction devices are received by annularly arranged elongated pockets which are deepest at their centers and gradually shallow or diminish in depth 25 toward their opposite ends, the rolling of the anti-friction devices up the inclined portions of their respective pockets causing the body center bearing and superposed car body to be elevated when the car is passing 30 around a curve, and the weight of the car body serving to cause the latter to automatically reassume and maintain its normal relation to the truck when upon straight track.

It is the primary object of the present invention to provide simple, durable and efficient means for causing the anti-friction devices to move or travel in unison up and down the inclined portions of the annular pockets or raceways of such center bearings 40 when the car is passing around a curve, thus maintaining all of the anti-friction devices in constant bearing contact with both of the center plates and thereby increasing the life of the center bearing by promoting 45 uniformity of wear and by substantially eliminating the possibility of crushing the anti-friction devices, which not infrequently occurs in present constructions as a result of one only or a few of the anti-friction devices at times having bearing contact with both of the center plates and, therefore, being at such times subjected to the entire load 50 of the car.

Minor objects and features of the inven-

tion, involving elemental combinations and 55 particular forms of construction, will hereinafter appear.

In the drawings illustrating the best mode in which I contemplate applying my invention: Figure 1 is a vertical section of a center bearing embodying my invention, the view being taken on the line 1—1, Fig. 2. Fig. 2 is a plan view of the center bearing illustrated in Fig. 1, the body center plate being omitted. Fig. 3 is a detail sectional 65 view, taken in the plane of the line 3—3, Fig. 2. Fig. 4 is a detail sectional view, taken on the line 4—4, Fig. 2, the parts being in their normal positions with the anti-friction ball occupying its lowest position. 70 Fig. 5 is a view corresponding to Fig. 4, but illustrating the relation of the parts when the anti-friction ball rolls up the inclined portion of the elongated pocket or raceway as the car passes around a curve. 75 Fig. 6 is a detail view taken on the line 6—6, Fig. 4, the ball being shown in plan. Fig. 7 is a vertical sectional view, taken on the line 7—7, Fig. 8, showing the application of my invention to a center bearing 80 wherein the truck center plate is formed as an integral part of the truck bolster; and Fig. 8 is a plan view of the construction illustrated in Fig. 7, the body center plate and body bolster being omitted. 85

I will now proceed to describe my invention more fully, so that others skilled in the art to which it appertains may apply the same.

In the drawings, 1 indicates the truck center plate and 2 indicates the body center plate of the center bearing. Each of these center plates is provided with an annular raceway for the reception of anti-friction balls 3. For the sake of economy of maintenance the raceways of the center plates are preferably formed in drop forged steel rings which fit into corresponding annular recesses in their respective center plates. The raceway for the balls 3 in the raceway 90 ring 4 of the truck center plate 1 is preferably formed as an annularly extending series of similar elongated bearing pockets 5 which are deepest intermediate of their ends and which incline upwardly or gradually 95 diminish in depth toward their ends. Each of these pockets is designed to accommodate one of the balls 3. The raceway 6 formed

2
in the raceway ring 7, instead of consisting of a series of elongated, inclined pockets, is preferably a continuous and complete annulus of the same cross-sectional form throughout, as more particularly illustrated in Figs. 1, 3, 4 and 5.

Interposed between the center plates 1 and 2 is an annular frame 8 which is provided with a circularly arranged series of apertures through which the balls 3 protrude. This frame 8, which is rotatable with respect to the center plates, may conveniently rest upon the upper face of the truck center plate 1, it being preferably retained in assembled relation with said center plate by means of clips 9 which are bolted or riveted to the center plate and which are provided with inwardly projecting ends 10 that overhang the margin of the frame 8. The frame 8 is adapted to constantly maintain the balls 3 in proper bearing engagement with the center plates and in correct spaced relation with each other. To this end, as will be readily understood upon reference to Figs. 4, 5 and 6, the frame 8 is designed to at all times remain in operative engagement with the balls and to permit the latter to travel in unison up and down the inclined portions of their respective pockets 5 without communicating the vertical movements of said balls to the frame. By this means it becomes impossible for any ball to lift the frame 8 and thus allow one or more of the remaining balls to lag behind and thereby escape the duty of bearing the proportionate part of the load. All the balls, therefore, since they move coextensively and at all times occupy corresponding positions with respect to the ball-receiving pockets 5, are necessarily in simultaneous bearing contact with the raceways of the center plates, and the load of the car is thus sustained equally by each of the balls.

In order to permit the frame 8 to have contact with the balls 3 at points in alignment with the median lines of the raceways or in the direction of travel of said balls, as well as for the purpose of facilitating the assembly and rotation of the balls with respect to the frame, it is preferred to form the inner faces of the curved, ball-retaining hoods 11 of the frame with projecting ribs 12, leaving clearances between the balls and the other inner portions of the retaining hoods. Not only does the frame 8 serve to cause the anti-friction devices to operate in unison, as heretofore explained, but it also excludes dirt from the raceways and prevents rattling and noise when the balls are in their lowest positions in the ball-receiving pockets 5.

In the modified form of construction illustrated in Figs. 7 and 8 the truck center plate, which is indicated at 1^a, is an integral part of the truck bolster instead of being

detachable therefrom. The body center plate is indicated by 2^a, while the balls are marked 3^a, the lower raceway ring is 4^a, the ball-pockets in the lower raceway ring are 5^a, the upper raceway ring is 7^a, the upper 70 annular raceway is 6^a, the frame is 8^a and the clips for securing the frame to the truck bolster are indicated at 9^a. The functions performed by these several parts are precisely the same as those performed by the 75 corresponding parts in the form of construction already described; and except for changes in the dimensions and mere matters of form, as, for example, the somewhat differently shaped clips 9^a and the lateral extensions 8^b which project from opposite sides of the frame 8^a and extend beneath the clips 9^a, the corresponding parts in the form of my invention which is illustrated in Figs. 7 and 8 are substantially of the same construction as those performing similar offices in the construction which is exhibited in the principal figures of the drawings.

I claim:

1. In a device of the character indicated, 90 the combination with relatively movable members which are adapted to move toward and from each other and which are provided with roller-engaging surfaces arranged at an angle to each other, of a frame interposed between said members, and anti-friction roller devices spaced with relation to each other and interposed between said relatively movable members and protruding on opposite sides of said frame, said rollers being adapted to simultaneously engage said roller-engaging surface of said relatively movable members in any of the several positions which such members may normally assume when rotated with respect to each other, and said frame being adapted to maintain the spaced relation of said roller devices with respect to each other when the relatively movable members turn with respect to each other.

2. In a device of the character indicated, the combination with a truck center plate, of a body center plate, anti-friction roller devices interposed between and engaging said center plates, said truck center plate having inclined means co-operating with said roller devices and adapted to cause a separation of said center plates upon a relative turning movement of the latter, and an apertured frame which is interposed between said center plates and through which said roller devices protrude, said frame being rotatable to permit the travel of said roller devices while maintaining them in spaced relation with each other as the said center plates turn, and said roller devices being movable vertically independently of said frame.

3. In a device of the character indicated, the combination with a truck center plate, of

- a body center plate, said center plates being provided with roller-engaging surfaces arranged at an angle to each other, anti-friction roller devices interposed between said plates and engaging said surfaces, an apertured frame also interposed between said plates, and means for restraining vertical movement of said frame with respect to one of said center plates while permitting the 10 rotation of said frame with respect to said center plate, said frame being adapted to maintain said roller devices in spaced relation with each other when said center plates turn with respect to each other and being 15 also adapted to permit said roller devices to move vertically independently of said frame.
4. In a device of the character indicated, the combination with a truck center plate 20 having a raceway therein formed with roller-receiving pockets having inclined ends, of a body center plate having a raceway therein, anti-friction roller devices operating in the raceways of the said center plates, 25 and means in fixed spaced relation to said truck center plate for retaining said roller devices in fixed spaced relation with each other when said center plates turn with respect to each other, said means being movable with the said roller devices, and said 30 roller devices being vertically movable with respect to said retaining means.
5. In a device of the character indicated, the combination with a truck center plate, 35 of a body center plate which is both rotatable and vertically movable with respect to said truck center plate, said center plates being provided with roller-engaging surfaces extending at an angle to each other, anti-friction roller devices interposed between and adapted to simultaneously contact 40 said center plates in any of the several operative positions to which said center plates may be rotated, and an apertured frame interposed between said center plates and seated upon the upper face of said 45 truck center plate, said roller devices protruding through the apertures in said frame and being movable therethrough to there-
- by vary the extent of their protuberance on opposite sides of said frame. 50
6. In a device of the character indicated, the combination with a center plate having a raceway comprising an annular series of elongated pockets which are deepest intermediate of their ends and which diminish in depth toward their ends, of a coöperating center plate provided with a raceway, balls interposed between said center plates and movable in said raceways, and a frame interposed between said center plates and adapted to retain said balls in fixed spaced relation with each other when said center plates turn with respect to each other, said frame being formed with a series of apertures adapted to receive said balls and being formed with hood portions which prevent said balls from passing through the apertures in said frame, and said balls being adapted to rotate said frame and being movable vertically with respect to said frame. 55 60 65 70
7. In a device of the character indicated, the combination with a center plate having a raceway consisting of an annular series of elongated pockets which are deepest intermediate of their ends and which gradually diminish in depth from their centers toward their ends, of a coöperating center plate having a raceway, balls interposed between said center plates and movable in 75 80 said raceways, and an apertured frame adapted to maintain said balls in fixed spaced relation with each other and to permit said balls to move vertically independently of said frame, said balls being adapted to impart a rotary motion to said frame and said frame being provided with hood portions having upon their interior faces projections which are adapted to engage 85 said balls. 90

In testimony whereof I affix my signature, in the presence of two subscribing witnesses.
